BEVERAGE DISPENSER

Charles A. Geddes, Rochester, N. Y., assignor to
 Richardson Corporation, Rochester, N. Y., a
 corporation of New York

Application June 13, 1932, Serial No. 616,917

1 Claim. (Cl. 225—23)

This invention relates to improvements in beverage dispensers, and has for its principal object the provision of simple and inexpensive means for reliably counting and registering each 5 operation of the faucet for dispensing beverage therefrom.

Another object of the invention is the provision of means for limiting the quantity of syrup dispensed with each operation of the faucet to 10 that required for a single glass or other container in which the beverage is served and means for registering each operation for withdrawing such measured quantity of syrup.

A further object of the invention is the provision of a counter with means for operating it to 15 register one unit each time the faucet is operated to dispense a glass of the beverage, the construction and arrangement being such that the counter is not operated until the valve is opened to permit 20 the discharge of the beverage, and in which the valve is not opened until the operating finger-piece has been moved to nearly its full extent, so that accidental operations thereof will not be registered or counted.

To these and other ends, the invention consists 25 in the construction and arrangement of parts that will appear from the following description when read in conjunction with the accompanying drawing, the novel features being pointed out in 30 the claim at the end of the specification.

In the drawing:

Fig. 1 is a side elevation of the dispensing devices of a beverage dispenser illustrating one possible embodiment of the invention, parts of 35 the casing being broken away;

Fig. 2 is a front elevation of the same, the casing for the counter being removed;

Fig. 3 is a transverse section taken substantially on line 3—3 of Fig. 1 and looking in the 40 direction of the arrow at said line, parts being removed to expose underlying parts;

Fig. 4 is a similar view showing parts in another position;

Fig. 5 is a similar view showing parts in still 45 another position; and

Fig. 6 is a section taken on line 6—6 of Fig. 5 and looking in the direction of the arrow at said line.

Referring particularly to the drawing, 1 represents the casing of a beverage dispenser of well 50 known type, having an opening therein in which is mounted a dispensing device comprising a support 2 fixed in the opening and carrying an outwardly projecting faucet member 3 on its outer end. The faucet member 3 has a syrup

measuring chamber 4 therein and an opening in its outer end in which a valve member 5 is revolvably mounted. Adjacent its forward end, it has a downwardly projecting discharge nozzle 6, and a discharge opening 7 in the faucet member connects the opening for the valve member with the discharge nozzle. A passageway 8 in the faucet member is connected with a suitable source of syrup supply in the dispenser casing and is adapted to be connected with a passage 9 between the valve opening and the measuring chamber by means of a passageway 10 in the valve member, whereby syrup from said source is conducted to the measuring chamber when the valve member is in its closed position. The faucet member has an upwardly projecting nipple 11 which provides an auxiliary measuring chamber 12 communicating with the measuring chamber 4 but which may be separated therefrom by means of a valve 13 seated on a valve seat arranged between the chambers 4 and 12. The valve 13 is fixed on the lower end of a hollow valve stem 14 slidably mounted in a centrally arranged opening in a thimble 15 threaded into the upper end of the nipple 11. The thimble 15 has enlarged openings in its ends, the lower one of which forms a part of the chamber 12 and the upper one is internally threaded for cooperation with a plug 16 which engages a packing for sealing the opening through which the valve stem projects. When the valve member is in said closed position to open the connection from the source of syrup supply to the measuring chamber, the syrup is free to flow to the measuring chamber until its level in the valve stem reaches its level in said source of supply. When the valve member is turned to open the valve or to the position shown in Fig. 6 of the drawing, the passageway from the source of syrup supply to the measuring chamber is closed by the valve member and an opening or passageway 17 in the valve member connects the front end of the passageway 9 with the discharge opening 7 to discharge the syrup from the measuring chamber to the discharge nozzle. Since a new supply of syrup cannot flow to the measuring chamber, the syrup will cease to flow from the opening 7 when the supply in the measuring chamber is exhausted and the valve member must be moved to closed position before a new charge of syrup can flow to 105 the measuring chamber.

Means are provided for mixing a suitable diluent with the syrup in the discharge nozzle or a mixing chamber 18 in its upper end. To this end, a second passageway 19 in the faucet member is 110

connected with a conductor 21 leading to a suitable source of supply, preferably under pressure, such as carbonated water. When the valve member is in closed position, the forward end of said 5 passageway is closed thereby; when, however, the valve member is moved to its open position, the passageway 22 therein connects its forward open end with the discharge opening 7 to permit the diluent to flow therefrom into the syrup in the 10 mixing chamber 18. Fixed to the rear end of the valve member 5 to turn therewith and having openings therethrough corresponding to its passageways is a gasket 23. A cap 24 is threaded in the front end of the faucet member to close 15 the same and has a threaded opening arranged centrally therein which receives a screw 25 having a pointed end arranged to axially engage the forward end of the valve member and may serve to clamp the gasket 23 into engagement with its seat 20 and lock the cap 24 against accidental displacement. A finger-piece 26 is secured in the valve member and projects outwardly therefrom through an elongated slot in the faucet member and serves as a convenient means for operating 25 the valve member. The parts thus far described form no part of the present invention except as they enter into combination therewith, and are fully described and claimed in separate applications filed of even date herewith.

30 The present embodiment comprises means for registering and counting each operation of the valve member to dispense a glass or stein of the beverage, so that the number of drinks dispensed is at once apparent. To this end, a counter 28 35 of any conventional or preferred form is mounted on the faucet member. Said counter is inclosed in a suitable casing 29 which may be secured thereto by a suitable lock 31, as shown, and has a counter scale 32 within convenient observation 40 of the attendant. Detailed description of the counter is deemed unnecessary here since it may be of well known type and forms no part of the present invention except as it enters into combination therewith. The counter has a shaft 33 45 projecting from its forward end whereby it may be operated by a reciprocatory movement. Secured on the front end of this shaft is an arm or finger 34 which resiliently engages the outer end of a stud or pin 35 by virtue of resilient 50 means within the counter which tends to turn its shaft in one direction. The pin 35 is slidably mounted in the faucet member and at its inner end engages the outer periphery of the valve member in the path of a cam slot 36 provided 55 therein. When the arm 34 is actuated against the tension of its spring, the parts are so timed that the first part of its movement is idle, but during the latter part of its movement, it operates the counter to advance the unit scale one 60

unit. When the valve member is in its normal inoperative position shown in Fig. 3, the inner end of the pin 35 engages the deepest or inner end of the cam 36 in the valve member, and in this position of the valve member the discharge opening 7 is closed. When the valve member is moved in a clockwise direction, as seen in the drawing, toward open position, the pin 35 rides up the cam 36 and moves the arm 34 against the tension of its resilient means and operates the counter just at the time when it approaches the end of the cam or periphery of the valve member, approximately shown in Fig. 4 of the drawing, at which time the passageways 22 and 17 are just about to register with the discharge opening 7 to permit the beverage to flow therefrom. A slight further movement to the right of the valve member from the Fig. 4 toward the Fig. 5 position and the inner end of the pin engages the outer periphery of the valve member and swings the arm 34 to the limit of its movement, at the same time the passageway 17 moves into partial registration with the opening 7 and the beverage begins to flow therefrom, although it is not brought into complete registration therewith until the 100 valve member reaches the limit of its movement, as shown in Fig. 5. By the arrangement shown, the counter is not operated to register until the valve is opened to permit the flow of the beverage so that it is impossible to withdraw any of the 105 beverage until the counter registers that fact. Moreover, an accidental partial movement of the valve member, as when clothing of the attendant catches the finger-piece 26 and accidentally turns it from the vertical position, is not effective to 110 actuate the counter unless moved to such an extent as to cause the flow of the beverage.

Although only one embodiment of the invention is shown and described herein, it will be understood that this application is intended to cover 115 such changes or modifications as come within the spirit of the invention or scope of the following claim.

I claim:

In a beverage dispenser, the combination with 120 a casing, of a faucet member mounted thereon, a rotatable valve member in said faucet member, means for turning said valve member in one direction to open the faucet and in the opposite direction to close the faucet, a counter including 125 an operating arm, means for actuating said arm comprising a pin slidably mounted in the faucet member in engagement with said arm and movable radially of the valve member, the latter having a recess to receive the inner end of the pin, 130 and a cam surface which forces the pin outwardly when the valve member is turned to operate the counter.
